SHOE HOLDER BRACKET

Leon Cohen, Downey, Calif.

Application March 11, 1936, Serial No. 68,236

6 Claims. (Cl. 211—35)

My invention relates principally to a bracket plate assembly in which a facing plate and a wall plate are joined together and these two plates have pressed out portions which form a socket 5 to receive a plug portion of a device to be supported by the bracket, the wall and facing plates being adapted for attachment to a wall post or other device.

Considered more specifically, my invention has 10 for an object and feature, an assembly of a wall and facing plate in which the facing plate has a horizontal slit and a portion of the plate adjacent the slit die pressed outwardly forming a projection having the sides and bottom portion 15 of the projection connected to the main body of the facing plate. The wall plate back of the pressed out portion of the facing plate has a portion thereof which is pressed forwardly, then, as these two plates are assembled face to face, 20 a socket is formed between the slightly forwardly pressed portion of the wall plate and the die pressed portion of the facing plate. The edge of this latter part of the facing plate adjacent the slit forms the upper edge of the socket, and 25 a plug may be inserted through the opening defined by a plane transverse portion of the facing plate at the slit and the side and front walls of the outwardly die pressed portion of the facing plate.

Another detailed feature of my invention relates to attaching the wall and facing plate together by a turned over bead formed at the peripheral edge of the wall plate.

Another feature of my invention in regard to the use of the brackets is in forming each bracket with an upper and lower socket and utilizing a pair of these brackets and having horizontal extensible bars connecting between the sockets. The bars have a portion spacing the main connecting part outwardly from a wall so that shoes or the like may be mounted on the bars, the heel of the shoe being caught over the upper bar and the sole of the shoe resting on the lower bar.

My invention is illustrated in connection with the accompanying drawing, in which,

Figure 1 is an elevation of a shoe holder using brackets made in accordance with my invention;

Figure 2 is a vertical section on the line 2—2 of Figure 1 in the direction of the arrows;

Figure 3 is a perspective view of the wall plate prior to forming the attaching bead;

Figure 4 is a perspective view of the facing plate prior to assembly with the wall plate; and

Figure 5 is a transverse section on the line 5—5 55 of Figure 2 in the direction of the arrows.

The bracket construction consists of a wall plate 11 which is preferably made in the form of a strip having parallel side edges 12 and rounded ends 13. The plate has forwardly pressed bosses 14, these bosses being quite shallow and being defined by parallel side edges 15 which are intended to be vertical when the bracket is vertical, and having upper and lower edges 16 joined to the side edges by a rounded corner. It will be seen by reference to Figures 2 and 5 that bosses 10 14 are only pressed outwardly substantially the thickness of the metal forming the wall plate. A characteristic of these bosses is that the marginal edge portions 15, 16 and 17 have on the outside, a sloping surface indicated at 18. Thus the 15 bosses are not formed with abrupt angles where the metal of the boss joins the metal of the wall plate, which is preferably in the form of a plane strip.

In assembling the wall plate with the facing 20 plate as hereinunder detailed, the wall plate is beaded over by a reverse fold on approximately the side lines indicated 19 (dotted) and at the upper and lower ends on the curved lines 20 (also dotted). Perforations 21 are formed in the 25 upper and lower ends of the wall plate.

The facing plate 25 is also made of a metal strip having a shape similar to that of the wall plate and being defined by parallel side edges 26 and rounded ends 27, these merging together. A 30 transverse slit 28 is formed, and an enlarged projection 29 is pressed outwardly preferably by a die pressing operation. This projection preferably has a face surface 30 which is preferably 35 plane and parallel to the surface of the main portion of the plate. The side walls 32 are bevelled to merge with the main portion of the plate 31. The bottom 33 has a greater bevel and on its inside surface 34 has a slope which is the same as the slope of the outside edge 18 of the 40 boss 14 on the wall plate. The upper portion of the projection thus has an upper edge 35 defined by the upper end of the face portion 30 and of the bevelled sides 32. The face plate is so proportioned that the measurement between the 45 side edges 26 is approximately equal to the measurement between the marginal folding lines 19 of the wall plate. This facing plate is provided with perforations 36 aligning with the 50 perforations 21 of the wall plate.

The two plates are assembled by placing the facing plate on the wall plate so that the boss 14 fits inside of the space formed by the projection 29, and, on account of the bevel 33 of the facing plate having the same slope as the 55

lower edge portion of the boss 14 there is a neat fit at the bottom of the boss and the lower portion of the projection 29, as shown in Figure 2. In addition, the side edges 15 of the boss and the 5 inside of the side walls 32 of the projection 29 also have the same slope of bevel, so that they neatly interfit, as shown by the transverse section in Figure 5. When these plates are assembled, a turned over bead 40 is formed by the portion 10 of the wall plate between the dotted line 19 and the peripheral edge of such plate. This bead firmly attaches the two plates together and aligns the perforations 21 and 36. The assembled plates therefore are characterized by having 15 a plane flat surface 41 on the back of the assembled plates, except for the slight indentation 42 formed at the back of the bosses 14. This structure develops a socket 43 which is defined by the face of the box 14, the inside of the projection 29 which has the face portion 30, the side walls 32 and the lower bevel 33. The top opening 20 of the socket is defined by the slit edge 28 of the face plate and the upper edge portions 35 of the projection 29. The bracket may be attached 25 to a wall or other structure by screws or the like inserted through the aligned perforations 21 and 36.

The use of brackets of this type is in using a pair of brackets, each having two sockets. An 30 upper supporting rail 50 is formed by two bars 51 which overlap each other and are parallel and are held in place to slide on each other by two collars 52, the collars being crimped or otherwise attached to the end portion of each bar. 35 Each of these bars has a horizontal end piece 53 which has a twist 54 and a down turned plug 55. The plugs at the opposite ends of the assembled bar fit in the sockets 43. The size of the plugs is in proportion to the size of the sockets so that 40 there is a tight fit and as the bosses may be slightly compressed, the plug is held tight in the socket, being confined between the projecting box 14 and the wall plate and the projection 29 on the facing plate.

45 The assembly of bars 50 may be made with the lower transverse portion of the bar placed further from the bracket than the upper bars, as shown in Figure 2, which provides for shoes being supported on the bars, the heel being caught 50 over the upper bar, and the sole resting on the lower bar. Manifestly, as the bar portions 51 overlap the brackets can be spaced at variable distances apart to accommodate a greater or a lesser number of shoes, the assembly thus forming 55 a shoe rack.

My invention also involves the method or procedure of forming the bracket in which by die 60 pressing operation the slit 28 is formed and the projection 29 is forced outwardly from the facing plate, this operation also forming the beveled side edges and the beveled lower end 33. In the 65 operation on the wall plate 12, the boss 14 is pressed outwardly by a suitable die, thus shaping the beveled edges to conform to the bevel or slope on the projection 29. These plates are then 70 fitted one on the other, the boss 14 functioning as a centering element in regard to the projection 29, or vice versa. Hence, the boss and the projection can only interfit in correct position to overlap the plates properly. Such plates

may then be secured together by the formation of a peripheral bead, that is, bending the marginal edge of one plate over the other. It will be manifest that any desired number of sockets may be formed on the assembled plates by forming an equal number of projections and bosses on the facing and wall plates. 5

Various changes may be made in the principles of my invention without departing from the spirit thereof as defined by the appended claims. 10

1. A holder bracket having a wall and a facing plate secured together, the facing plate having a slit, a projection formed at one side of the slit forming a space between the plates with an entrance to said space adjacent the said slit, 15 the wall plate having a forwardly projecting boss extending partly into the said space and defining with the projection a socket, the socket being adapted to receive a plug inserted through the opening adjacent the slit. 20

2. A holder bracket as claimed in claim 1, the boss having beveled edges and the projection having sloping sides to interfit with the bevel edges of the boss.

3. A holder bracket having a wall and a facing 25 plate both with the main portion of their surfaces flat, means securing said plates together, the facing plate having a slit, the material of the facing plate forming a projection at one side of the slit, said projection having beveled 30 side walls and a beveled end wall, the projection having edges adjacent the slit, the wall plate having a boss with beveled side edges, the beveled edges of the boss contacting and interfitting with the beveled walls and ends of the projection, 35 the front face of the boss being in substantial alignment with the front face of the facing plate whereby a socket is formed defined by the boss and the projection and adapted to receive a plug inserted through an opening defined by the edges 40 of the projection.

4. A holder bracket as claimed as claim 3, the means securing said plates together comprising a marginal bead formed on one plate and clamping 45 the edges of the other plate.

5. A holder as claimed in claim 3, there being a pair of holder brackets and each having an upper and a lower socket with plugs fitted therein, said plugs being connected to horizontal end pieces, and the end pieces each being attached to a horizontal bar, the said bars overlapping and being connected by collars, whereby the length of the bars between two brackets may be adjusted. 50

6. A holder bracket comprising a wall and a facing plate secured together, both of said plates 55 having their main surface in a plane, the facing plate having a slit, the material of the facing plate at one side of the slit forming a projection with front and side walls, said front and side walls having an edge adjacent the slit, the 60 said edges with a portion of the facing plate forming an opening, the space below the opening forming a socket, the wall plate defining the back of the socket whereby a plug may be inserted in the said socket, the wall plate having a boss extending into the space back of the projection, 65 the front of the boss forming the portion of the wall plate defining the recess.
